(57) **CLAIM**

The ornamental design for a clothing article with detachable fastenable extended inseam crotch as shown and described.

DESCRIPTION

FIG. 1 is a perspective view of the invention;
FIG. 2 is a front elevation view thereof;
FIG. 3 is a back elevation view thereof;
FIG. 4 is a left side elevation view thereof;
FIG. 5 is a right side elevation view thereof;
FIG. 6 is a top view thereof;
FIG. 7 is a bottom view thereof; and,
FIG. 8 is a bottom perspective angled view thereof.
The broken lines in the drawings are used to illustrate the bottom edge hem and zipper and represent portions of the article which form no part of the claimed design.

1 Claim, 6 Drawing Sheets
